UNITED STATES PATENT OFFICE.

JAMES A. O'NEIL, OF LYNN, MASSACHUSETTS, ASSIGNOR TO GENERAL ELECTRIC COMPANY, A CORPORATION OF NEW YORK.

LIGHTING UNIT.

Application filed March 9, 1923. Serial No. 623,628.

To all whom it may concern:

Be it known that I, JAMES A. O'NEIL, a citizen of the United States, residing at Lynn, in the county of Essex, State of Massachusetts, have invented certain new and useful Improvements in Lighting Units, of which the following is a specification.

My invention relates to lighting units and in particular to units adapted for lighting 10 highways.

Heretofore lighting units for highways have been provided in which a light source is located above a reflector having two wings so placed as to resemble an inverted V.

15 With a device of this character two oval beams are produced, one extending in one direction along the road and the other one in the opposite direction. One of these beams is produced by one wing and the

20 other one by the opposite wing of the V. However, if the lamp is set to one side of the road or beyond the sidewalk, the wings of the V must be rotated about a vertical axis so as to throw the beams into the road.

25 As a result of this rotation, the wings will separate at the hinge, so to speak, leaving a V shaped crack or opening through which the light from the light source passes straight down to the ground without striking either side of the reflector. This of course, renders the beam less intense and consequently less effective. Although rotating the wings operates to throw the beams into the road, nevertheless the beams that

30 are thrown across the road lie with the major axis of the oval at an angle with the street, one end of the oval overlapping the sidewalk on one side of the street and the other end overlapping the sidewalk on the

35 opposite side. This last objection has been remedied to some extent by other improvements, but these have not done away with the necessity of separating the wings at the hinge. It is the object of my invention to 40

45 overcome this objection by substituting or providing instead of reflectors, refractors of a certain character. These refractors are arranged V shaped with the wings separated above, like an upright V instead of below as an inverted V. These refractors I have provided with prismatic ribs running parallel to each other. If the light

50 unit is to be located in the middle of the road the ribs are run parallel to the ground. If the unit is located on one side of the

street, the ribs will run parallel to each other but will all slant in one direction downward toward the street. If the unit is located on the opposite side of the street they also slant toward the street and the ribs on one side of the street will not be parallel to those on the opposite side of the street. With this arrangement the beam may be placed where it belongs in the road with the major axis of the oval, where the beam strikes the ground, running parallel with the center of the road. This can be accomplished without having to separate the refracting plates at the hinge.

It is also the object of my invention to 70 provide other details of improvements to increase the efficiency and serviceability of a lighting unit of the above character.

The means for accomplishing the foregoing and other useful ends are hereinafter 75 more fully set forth and claimed.

Referring to the accompanying drawings:

Fig. 1 shows a light unit in side elevation partly in section on line 1—1, Fig. 2, with the refracting plates in place;

Fig. 2 is a bottom view of the same;

Fig. 3 is a front view in elevation of the light unit. In this figure the hood that holds the refracting plate is more clearly shown;

Fig. 4 is a front view in elevation of one of the refracting plates in which the ribs are shown running parallel with the base of the plates;

Fig. 5 is an end view of the same;

Fig. 6 shows in top view the two refracting plates of the unit, Fig. 1, with the frame removed. In this figure, ovals are shown on either side representing the beams from the unit as they meet the ground;

Fig. 7 is an end view of the plates, Fig. 6;

Fig. 8 is a view similar to Fig. 6, except that all of the ribs of one plate are shown sloping in one direction toward the base line, while the ribs of the opposite plate are shown sloping in a different direction from the same line;

Fig. 9 is an end view of the plates, Fig. 8 and is similar to Fig. 7;

Fig. 10 is a front view of Fig. 9 from 105 right to left;

Fig. 11 is a front view of Fig. 9 from left to right and;

Fig. 12 is an enlarged section of the glass plate showing the path of the light.

Referring more in detail to the accompanying drawings, the top of the unit, Fig. 1, is provided with a paraboloidal reflector A, which reflector rests upon a hood-like frame B. The upper part of the frame is tubular and is cut on opposite sides in a downwardly sloping direction to resemble the letter V. These sloping sections are in the nature of windows opposite each other 10 in which the refracting plates are mounted. These plates are made of glass, the interior faces of which are provided with suitable ribs which may extend parallel to each other and parallel to the base of the plate as in 15 Fig. 4. This, of course, means that these ribs run parallel to the lower edge of the hood as is the case when the unit is located in the middle of the road. These parallel ribs are shown not only in Fig. 4 but also in 20 Figs. 3, 2 and 6. As indicated in Fig. 2, a unit is provided with two glass plates 2 and 3 one on each side of the hood B. These two plates appear also in Figs. 6 and 7. As indicated in Fig. 6, the plate 2 produces a 25 beam to the left which as it strikes the ground forms an oval, indicated in the drawing by the oval F. Similarly the plate 3 throws a beam in the opposite direction which produces the oval G. The major axes 30 of both these ovals lie in the same straight line along the middle of the road.

When the unit is placed on either side of the street instead of in the center, the ribs are made to slope, as indicated in Figs. 8, 35 10 and 11, toward the base of the planes, i. e., toward the line where the two planes meet. If the unit is intended for the right side of the street looking in one direction, the ribs are made to slope toward the street. 40 If the unit is intended for the opposite side of the street, the ribs are caused to slope also toward the street which, of course, means that in either case the ribs slope toward a plane perpendicular to and along 45 the middle of the street. With such provision, the unit may be shifted to one side or to the other of the line that coincides with the major axes of the ovals F and G and yet retain the ovals as indicated in Fig. 50 6 with their axes parallel and coincident with the center of the street. Referring to Fig. 12, I show in this figure the ribs on the inside of the plates. These ribs are prismatic in character. The rays of light, such 55 as the ray 4, come from above from the parabolic reflector and strike the surface 5 of the prismatic rib 6 at an angle such as to produce total reflection in the direction of the ray 7. All of the other prism surfaces 60 8, 9 etc., corresponding to the surface 5 run parallel to surface 5, and therefore each of these surfaces causes total reflection. As the rays, such as the ray 7, emerge from the outer surface 10 of the glass plate 11, they 65 suffer an upward refraction as indicated in

the drawing. However, the beam that passes out of the surface 10 slopes gradually down toward the surface of the road as indicated in Figs. 8 and 12. The upper surfaces 12 of the ribs are all parallel and 70 horizontal and through these surfaces the rays pass into the glass. As indicated in Fig. 12, the inner border of the upper surfaces 12 may be made irregular in order to increase the diffusing effect upon the light. 75 This construction is optional inasmuch as the inner surface 12 may be smooth.

In the construction of the unit the parabolic reflector A is secured to the hood B in any suitable manner. As shown in the drawing a source of light C lies within the unit at or about the focus of the reflector A. This source of light may be secured in any suitable manner to the reflector. The reflector may be provided with an opening at 85 the top through which the light socket may project as indicated.

With a unit constructed in accordance with my invention, the beams of light are thrown on the road without wasting any or little light beyond the sidewalks or edges of the road. I avoid waste of light also by preventing any rays from passing between the glass plates at the bottom of the unit. Furthermore, by maintaining the prismatic ribs on the inside of the closure I minimize 90 the possibility of dirt and dust accumulating on the ribs. It will be seen that with the construction shown in Figs. 8 through 11, the glass plates are retained closed and also slope 95 toward each other and toward a plane at right angles to the longitudinal axis of the unit. Furthermore, the longitudinal axis of each of the prismatic ribs slopes also toward the said perpendicular plane. It will 100 be understood that the prismatic ribs may deviate from a straight line provided they have a common general direction. Furthermore, with the construction shown, it will 105 be seen that the main beam projected by the reflector A is divided into two diverging beams by said prisms, each beam having its 110 axis in a separate axial plane, i. e. in a separate plane passing through the longitudinal axis of the unit.

What I claim as new and desire to secure by Letters Patent of the United States, is:

1. In a light unit, a series of planes in which the rays from a beam of light are changed in direction, said planes all sloping toward a line that lies across the beam, said planes divided into two groups in each of which the planes run parallel to each other, the planes of one group running in one direction and the planes of the other group running in a different direction, each plane forming the side of a separate prism, all of the prisms in one group having a face common to a given surface, and all of the prisms in the other group having a face common 125

- to a different surface, said surfaces sloping toward each other and meeting in said line.
2. In a light unit, a pair of glass planes sloping toward each other and meeting in a line at right angles to the major axis of the unit, and prismatic ribs in said planes for changing the direction of the light from the unit, said prismatic ribs all sloping toward said line.
- 10 3. In a lighting unit a reflector and a light source for producing a beam along the axis of the unit, a V-shaped transparent closure for said unit in the path of said beam with the sides of the V sloping toward the axis of the unit, and prismatic ribs in said sides for dividing the main beam into two diverging beams, the longitudinal axes of which slope toward a plane perpendicular to the longitudinal axis of the unit whereby the beam is divided into diverging beams, the axes of which beams lie in two separate axial planes of the unit.
- 15 4. In a light unit a source of light, a transparent element enclosing the light source having a series of prismatic elements each having a plane in which rays from the light source are changed in direction after entering the element, the axis of said elements all sloping toward a plane perpendicular to the longitudinal axis of the unit, said planes sloping with respect to the original direction of the changed rays at an angle less than the critical angle of total reflection whereby the beam is divided into diverging beams, the axes of which lie in two separate axial planes of the unit. 25
- 20 In witness whereof, I have hereunto set my hand this fifth day of March, 1923.

JAMES A. O'NEIL.
